UNITED STATES PATENT OFFICE.

ALBERT J. WEATHERHEAD, OF CLEVELAND, OHIO.

FORCE AND DRAIN FAUCET.

SPECIFICATION forming part of Letters Patent No. 319,647, dated June 9, 1885.

Application filed January 24, 1885. (No model.)

To all whom it may concern:

Be it known that I, ALBERT J. WEATHERHEAD, of Cleveland, in the county of Cuyahoga and State of Ohio, have invented certain new and useful Improvements in Force and Drain Faucets, of which the following is a specification.

The nature and objects of this invention will fully appear from the subjoined description, when considered in connection with the accompanying drawings, in which—

Figure 1 is a sectional view of my faucet, air-pump, and a barrel, showing their construction and relative positions in working order in connection with a refrigerator. Fig. 2 is a detached view of the air-pump, showing manner of securing it to the wall of the refrigerator in connection with the faucet and the manner of operating it in combination therewith. Fig. 3 is an end view of the faucet, showing handle for operating it. Fig. 4 is a cross-section on line *x x* of faucet in Fig. 1.

A represents the front wall of a refrigerator, supporting the faucet F and air-pump P. The faucet consists of a tube or barrel, B, made perfectly straight in that part which is inserted through the wall A, the inner end being screw-threaded and provided with a nut, b, for firmly securing it therein, the outer portion being finished and having flange b', bearing against the outside surface of the wall A. The outer end is made open, with a tapering bore, and has a discharge-branch, b².

C is an inner tube fitted into the said tube or barrel B. It is made preferably straight and plain, except at or near its outer end, where it has a tapering exterior, which fits closely into the taper of tube B. It also projects beyond the tube B, and is provided with a handle, H, and has an opening, c, which registers with the discharge-opening b². The inner end of said tube C projects considerably beyond the inner end of the tube B, and is held therein by means of a ring, c', and a short stiff spiral spring, c².

D is a crank fixed onto the end of said tube C by means of a set-screw, d. This holds the ring or washer c' against the spring. To the inner end of said tube C is attached a hose, E, by means of a screw-cap, e, connecting it with a keg, K, having a drain-plug, G.

The air-pump consists of an open cylinder, I, supported on a bracket, J, secured to the inside surface of the wall A by means of the nut b, which also secures the faucet. The upper end of said cylinder is closed with a head, M, secured by bolts i i, reaching from the ring on the bracket J, outside of the cylinder.

N is a plunger consisting of a disk having a split lug, n, in which is pivoted a pitman, L, connecting it with the crank D.

The head M is provided with two valves, t u. t is the suction-valve for drawing air into the cylinder, and u is the discharge-valve, and is connected by hose R to a hollow spigot, V, in the upper side of the keg K.

The operation of this device is as follows: The passage-way for the liquid from the keg is through hose E and the tube C. To draw liquid, the handle H is turned down one-quarter, as seen by dotted lines in Fig. 4. This gives a quarter-turn to the tube C, within the tube B, bringing the opening c in communication with the discharge, and at the same time it has pushed the plunger up into the cylinder, as seen in Fig. 1, thereby forcing air into the keg.

It will be noticed by referring to Fig. 5 that the opening c does not come opposite to the discharge until the plunger has made two-thirds stroke, so that the air is forced into the keg in advance of the withdrawal of liquid.

Having described my invention, I claim as follows:

The combination, with faucet F, consisting of the tube or barrel B, having open end with tapering bore and provided with discharge b², and the tube C, having tapering end fitted to fill said tapering bore and having opening c, registering with said discharge b², of handle H, the inner end projecting through barrel B, and held by the ring c' and spring c², and provided with the crank D, connected to and operating the piston of the pump P, substantially as described, and for the purpose specified.

ALBERT J. WEATHERHEAD.
